UNITED STATES PATENT OFFICE.

JOHANN SCHULER, OF BOCHUM, GERMANY.

RAIL-JOINT.

SPECIFICATION forming part of Letters Patent No. 508,580, dated November 14, 1893.

Application filed November 28, 1892. Serial No. 453,416. (No model.) Patented in Germany August 10, 1890, No. 55,476, and September 2, 1891, No. 63,094.

To all whom it may concern:

Be it known that I, JOHANN SCHULER, engineer, a subject of the King of Prussia, and a resident of the city of Bochum, Germany, have invented a new and useful Improvement 5 in Rail-Joints, (patented to me in Germany by Patents No. 55,476, dated August 10, 1890, and No. 63,094, dated September 2, 1891,) of which the following is a specification.

10 The old style of fish-plate joint, still very commonly used in railways, is unsatisfactory, as is well known, because, when the parts become a little worn if not before, it permits the near rail-end to be independently depressed 15 by each approaching car-wheel to a sufficient extent to produce a more or less violent shock, with its familiar sound, when the wheel strikes the adjoining rail-end in passing each joint. Various means have heretofore been proposed 20 for meeting this difficulty.

The present invention consists in certain novel combinations of parts, hereinafter set forth and claimed.

Its main object is the better avoidance of 25 such shocks, together with such accompanying noise, at rail-joints.

Another object is to provide for readily tightening such rail-joints to take up wear.

A sheet of drawings accompanies this specification as part thereof.

Figures 1 and 2 of the drawings are cross-sections of my improved rail-joint; and Fig. 3 is an elevation of the same.

Lines numbered 1, and 2, across Fig. 3 indicate the planes of the respective cross-sections correspondingly numbered, and like letters of reference indicate corresponding parts in all the figures.

In my improved rail-joint, the fish-plates, 40 *l*, are "Z-shaped" in cross-section, and are fitted to what are known as T-rails, A, B, so as to wedge themselves tightly between the head and the broad foot or flanges of the rail when the fish-plates are drawn together by the bolts 45 *b* which pass through the customary holes and slots in the fish-plates and rail-webs. Each fish-plate is further provided at midlength with a hole *a* in its downwardly projecting portion *l'*, which hole extends downward from 50 immediately above the plane of the bottom of the rail, and is fitted to a key or keys, *o*, or

o, n, which extend on both sides of the spaces between the rail-ends, and bridge the spaces between said lower portions of the fish-plates at bottom, so as to support the rail-ends from beneath, and preclude any depression of one without a corresponding depression of the adjoining end. 55

To provide for taking up wear in the joint, a wedging key *n* is used in connection with the key proper *o*, so that the joint may be tightened from beneath by a blow of the track-walker's hammer. Said wedging key is provided with notches *r*, and a locking bar *u*, accommodated together with the keys by said holes *a*, is provided with suitable spring bends *u'* at its ends to coact with said notches *r* as automatic locking devices, their extremities springing from notch to notch when the wedging key is driven in. 70

To reinforce the joint at midlength where the strain and wear are greatest, and to provide for tightening the joint laterally at this point, the fish-plates *l* are notched as shown at *l'* in Figs. 1 and 2, and a pair of supplemental plates *m*, approximately L-shaped in cross-section, and each provided with a pair of bolt-holes, are fitted between the middle portions of said fish-plates *l* and the head of the rail. Converging upper portions *m'* of 80 these plates *m* are admitted beneath the head of the rail by said notches *l'*, and vertical portions of the plates are provided with bolt-holes fitted to a central pair of longer screw-bolts *b'*, which take the place of a pair of the ordinary bolts *b* in this arrangement. By tightening said bolts *b'*, the reinforcing plates *m* are drawn into place, and the joint is effectively tightened and strengthened. 85

The devices for supporting and tightening the joint from beneath might obviously be used without said laterally reinforcing and tightening devices. A joint having thus the improved bottom keys and locking devices, without said supplemental plates *m* and bolts *b'*, would be represented by Fig. 2, in which these parts are omitted. Said locking notches *r* and dogs *u'*, as they may be termed, may be used only at one end of the wedging key; and other like modifications will suggest themselves to those skilled in the art. 95 100

Having thus described the said improve-

ments, I claim as my invention and desire to patent under this specification—

1. The combination with adjoining rail-ends of a pair of fish-plates l having downwardly extending portions l' provided at midlength with holes a , a horizontal key o supported within said holes, a wedging key n supported in like manner and provided with notches r , and a locking bar u supported in like manner and coacting with said notches to lock said wedging key, substantially as hereinbefore specified.

2. The combination with adjoining rail-ends of a pair of fish-plates l having downwardly extending portions l' provided at midlength with holes a , and a horizontal key o , a wedging key n and a subjacent locking bar u supported within said holes, said wedging key having notches r at bottom and said locking bar having spring bends u^2 to coact with said

notches as dogs, substantially as hereinbefore specified.

3. The combination with adjoining rail-ends of a pair of fish-plates l held in place by ordinary screw bolts b , and having top notches l^2 at midlength, a pair of reinforcing plates m having converging upper portions m^2 admitted beneath the head of the rail by said notches and each provided with a pair of bolt-holes, and a pair of screw-bolts passing through said bolt-holes, for reinforcing and tightening the joint in the manner hereinbefore set forth.

In testimony whereof I have signed my name to this specification in the presence of 35 two subscribing witnesses.

JOHANN SCHULER.
